BOILER CLEANER

Charles S. Turner, Detroit, Mich., assignor to
Diamond Power Specialty Corporation, De-
troit, Mich., a corporation of Michigan

Application February 10, 1930, Serial No. 427,375
Renewed July 11, 1935

6 Claims. (Cl. 122—392)

This invention relates to boiler cleaners and has particular reference to a boiler cleaner in which a blower element is adapted to discharge jets of cleaning fluid adjacent portions of the boiler to be cleaned.

One of the objects of this invention is to provide a novel means for mounting a blower element within a boiler, whereby the blower element will be mounted for movement relative to the portions of the boiler to be cleaned so that jets of cleaning fluid may be directed toward spaced boiler surfaces to be cleaned.

A further object of this invention is to provide a bearing for a blower element which bearing will be simple in construction and of such a character that the usual bearing brackets normally positioned within the boiler may be entirely eliminated.

Other objects and advantages of the invention will become more apparent as the following description proceeds, particularly when reference is had to the several embodiments of the inventive idea disclosed in the accompanying drawings wherein,

25 Figure 1 is a semi-diagrammatic sectional side view of a boiler showing the arrangement of the tubes therein and a blower element supported adjacent these tubes in accordance with the teachings of this invention.

30 Figure 2 is a fragmentary sectional view taken substantially on the line 2—2 of Figure 1.

Figure 3 is a fragmentary sectional view taken substantially on the line 3—3 of Figure 1.

Figure 4 is a sectional view taken substantially on the line 4—4 of Figure 1.

Figure 5 is a view similar to Figure 4 showing a different type of blower element supported adjacent the tubes.

Figure 6 is a view similar to Figure 1 showing the invention applied to a different type of boiler, and

Figure 7 is a sectional view taken substantially on the line 7—7 of Figure 6.

Referring then particularly to the drawings wherein like reference characters designate corresponding parts throughout all views, there is illustrated in Figure 1 a boiler of the bent tube type, this boiler including a pair of lower drums, one of which is shown and designated by the reference character 10, and three upper drums, two of which are shown and designated by the reference characters 11 and 12, respectively. It will be understood that the showing in Figure 1 is of a portion only of the boiler, the boiler being

symmetrical on opposite sides of a vertical center line passing through drum 12.

In accordance with the usual practice, the drums 10 and 11 are connected by a plurality of boiler tubes 13 arranged in rows to form a bank 5 of tubes 14 adjacent the one side of the boiler. To facilitate future reference to certain rows of the tubes, the outermost two rows of this bank are designated by the reference characters 15, 16, 17 and 18, respectively.

In accordance with the usual practice, baffles 19 and 20 are arranged within the bank 14 for directing the products of combustion adjacent the tubes 13 and if desired, suitable blower elements 21 and 22 may be associated with the baffle 20 15 for directing jets of cleaning fluid adjacent the lower outside portion of the bank of tubes 14.

The present invention contemplates in particular the provision of a novel type of bearing for supporting blower elements 25 and 26 adjacent the upper outside edge and the lower inside edge, respectively, of the bank of tubes 14. To accomplish this, certain of the tubes in row 15 are displaced or offset as at 27 to cooperate with the tubes in row 16 as at 28 to provide a bearing for the element 25. Thus alternate tubes in the row 16 may be omitted and opposite tubes in the row 15 may be bent inwardly through the spaces formed in the row 16 by the omission of the tubes and then backwardly into the row 15, whereby a crotch is formed between the row of tubes 16 and the deformed portions 27 of alternate tubes in the row 15, in which the blower element may rest. A similar arrangement is shown for supporting the blower element 26, it being noted that each alternate tube in row 18 is omitted and each alternate tube in row 17 is bent or displaced as at 30 to extend outwardly into the spaces formed in the row 18 by the omission of the tubes in this row and to thus cooperate with the tubes in this row to form a bearing as at 31 for the blower element. It will be obvious that the blower element will thus be supported throughout its length between these rows of tubes and may rotate in the bearings formed by these tubes to direct jets of cleaning fluid adjacent the tubes to clean the same.

Extending from the drum 10 to the drum 12 is a bank of tubes 35, and extending from the drum 12 to the other of the lower drums (not shown) 50 is a second bank of tubes 36. These two banks of tubes are arranged at an angle to each other whereby a V-shaped space 37 is formed between the same, and it constitutes a feature of this invention to displace certain of the tubes of these 55

banks to support a blower element 38 in the space 37.

Referring then particularly to Figures 3 and 4, it will be noted that alternate tubes in the rows 5 39 and 40 are omitted and that alternate tubes in the rows 41 and 42 are bent laterally to span the space between the banks 35 and 36. Thus alternate tubes 45 from row 41 extend laterally through the openings formed in row 39 by the 10 omission of tubes therein, across the space 37 and then upwardly in the row 40 in the spaces formed by the omission of the tubes in this row, for connection to the drum 12. Similarly alternate tubes 46 in the row 42 extend laterally 15 through the openings formed in row 40 by the omission of the tubes in this row across the space 37 and then upwardly in row 39 in the spaces formed by the omission of the tubes in this row for connection to the drum 12. At the point 20 where the tubes 45 and 46 cross, midway between the banks of tubes, suitable wearing pads 47 may be welded or otherwise fixed to these tubes to provide a bearing for the blower element 38. Thus the blower element may be rotatably supported between the two banks of tubes upon the 25 deformed or displaced portions of the boiler tubes for directing cleaning fluid adjacent the portions of the boiler to be cleaned.

In Figure 4 a telescopic blower element is 30 shown mounted in the space between the banks 35 and 36 and by reference to this figure it will be noted that the blower element 38' extends through an opening 50 in the boiler wall 51 for rotatable mounting in a suitable head 52 through 35 which cleaning fluid is supplied to the element. In its retracted position the blower element will be substantially entirely housed within the opening in the boiler wall, while in its extended position it will be supported by the tubes 45 and 46, 40 as will be clearly apparent by reference to the drawings. The blower element may be rotated by means of a gear 53 fixed to its end within the head 52, this gear being driven by a pinion 54 fixed to a shaft 55 which in turn is actuated by a 45 sheave wheel or the like 56. A flexible member 57 may be connected to the inner end of the blower and operatively associated with a brake drum 58 for braking extension of the blower element under the pressure of the cleaning fluid.

50 In Figure 5 a rotatable blower element 38" is shown mounted in the space 37, this blower element having a rotatable bearing on the pads 47 and having its outer end mounted in a suitable head 60 from which it receives cleaning fluid in 55 accordance with the usual practice. As is customary, in blower elements of this character, a sheave wheel 61 may be provided for driving a pinion 62 which in turn engages a gear 63 fixed to the blower element for rotating the latter.

60 In Figures 6 and 7 the invention is shown as applied to a boiler of the cross drum horizontal tube type. In a boiler of this type the tubes are arranged in rows which extend in an incline across the boiler to form a bank of tubes 65. 65 In this construction the uppermost row of tubes is designated by the reference character 66, while the lowermost row of tubes is designated by the reference character 67.

In accordance with the usual practice, blower 70 elements 70 are arranged transversely of the rows of tubes for directing jets of cleaning fluid through the bank of tubes to clean the same. The blower elements 70 arranged at the top of the bank are supported on the row of tubes 66, and 75 it forms a feature of this invention to deform or

displace alternate tubes in this row to form offset portions 71 which extend over the blower elements 70, as clearly shown in the drawings. Thus the blower elements are fixed against sliding movement longitudinally of the boiler tubes, the offset 5 or displaced portions of the tubes forming bearings in which the blower elements are rotatably journalled.

At the base of the bank 65 the blower elements 10 10 are directly beneath the row 67 and are supported in juxtaposition to this row by offset portions 12 of alternate tubes which extend around the blower elements to provide bearings for the same. Thus the blower elements may be rotatably supported directly below the bank of tubes 15 15 by certain of the tubes which are displaced to provide bearings.

From the above it is believed that the structure and operation of the invention will be clearly apparent. In each case the blower elements are 20 supported adjacent the tubes to be cleaned by offset or displaced portions of the tubes which form bearings for receiving the blower elements. Thus the invention in its broader aspects contemplates the combination in a boiler of a tube displaced from its normal position to provide a bearing for a blower element whereby the blower element may be supported for movement within the boiler without mounting in the boiler expensive and heat-absorbing bearing brackets. Thus the 30 blower elements may be mounted in the desired positions by utilizing the boiler tubes as bearings and may be rotated or otherwise moved dependent upon the type of cleaning desired.

While several embodiments of the inventive idea 35 have been described with considerable details, it is to be understood that the description is for the purpose of illustration only and is not definitive of the limits of the inventive idea. It will be readily apparent that the boiler tubes may be 40 readily deformed or displaced in numerous ways other than those disclosed to accomplish the results desired, and applicant therefore reserves the right to make such changes in the details of construction and arrangement of parts as will fall 45 within the purview of the attached claims.

What I claim as my invention is:

1. In combination, banks of boiler tubes, said banks being spaced from each other throughout substantially their entire lengths, and a blower 50 element arranged between said banks, certain tubes only of said banks being bent laterally to span the space between said banks and crossing each other at the midpoint between said banks to provide bearings for said blower element. 55

2. In combination a plurality of boiler tubes, the normal arrangement of the tubes being such that the tubes are not adapted to adequately support a blower element, and a blower element disposed adjacent said tubes, certain of said tubes having portions so displaced out of their normal positions as to constitute a support for the blower element. 60

3. In combination a plurality of boiler tubes, the normal arrangement of the tubes being such that the tubes are not adapted to adequately support a blower element, and a blower element disposed adjacent said boiler tubes, certain of said tubes having portions so displaced as to cooperate with others of said tubes to limit movement of the 65 blower in a plurality of directions relative to the boiler tubes. 70

4. In combination, a plurality of boiler tubes disposed at an angle to the horizontal, and a blower element disposed substantially horizontal- 75

- ly adjacent said boiler tubes, certain of said boiler tubes having portions so displaced out of their normal position as to constitute substantially horizontal supports for said blower element.
5. In combination a plurality of substantially vertically disposed boiler tubes, and a blower element disposed substantially horizontally adjacent said boiler tubes, certain of said boiler tubes having portions so displaced out of their normal
- 10 positions as to cooperate with others of said tubes to form upwardly opening angularly shaped supports for the blower element.

6. In combination, rows of boiler tubes, said rows of boiler tubes being spaced from each other throughout substantially their entire length, and a blower element arranged between said rows of boiler tubes, certain tubes only of said rows being bent laterally to span the space between said rows and crossing each other between said rows to provide supports for said blower element.

CHARLES S. TURNER. 10
